UNITED STATES PATENT OFFICE.

ALFRED F. TARDIE, OF RIVERSIDE, RHODE ISLAND.

CARBON-MONOXIDE BURNER.

Application filed April 15, 1922. Serial No. 553,240.

To all whom it may concern:

Be it known that I, ALFRED F. TARDIE, a citizen of the United States, residing at Riverside, in the county of Providence and 5 State of Rhode Island, have invented certain new and useful Improvements in Carbon-Monoxide Burners, of which the following is a specification.

The invention has for an object to provide a readily attachable device for furnace doors, so constructed that air admitted through the ordinary draft openings of such doors will be super-heated and projected into the fire-box in such a manner as to 10 cause combustion of carbon monoxide gases. As is well known, in all furnaces of the ordinary type, carbon monoxide gas is formed with carbon dioxide indicating incomplete combustion of the fuel and representing a loss. It is also well known that carbon monoxide is an inflammable gas, although it will not ignite at ordinary temperatures as readily as gases ordinarily used for heating and illumination. It will burn, 15 however, when combustion is supported by maintenance of a proper temperature in the gas to be ignited and the one to support combustion. It is an object of my invention, therefore, to take advantage of these facts and provide a simple means for attaining 20 the ends in view. It is an important object of the invention to enable the provision of such apparatus at a low cost, which will be readily adaptable without numerous different 25 sizes of patterns, to various furnace doors. It is a further aim to simplify manufacture of a device of this kind having a housing within which there are a number of plates having small foraminations. It is a 30 still further object to provide a novel means for directing air in tortuous paths through such device in conjunction with the foraminated plates.

Additional objects, advantages and features of invention reside in the construction, arrangement and combination of parts, as will be understood from the following description and accompanying drawings, wherein,

50 Figure 1 is a vertical section of a fire-box in a furnace the door of which is equipped with my invention,

Fig. 2 is a top view of my appliance in use, part of the door frame being shown in 55 section,

Fig. 3 is a front elevational view of the appliance with parts broken away,

Fig. 4 is a horizontal sectional view on the line 4—4 of Fig. 3, looking downwardly,

Fig. 5 is a vertical sectional view on the line 5—5 of Fig. 3.

Fig. 6 is a top view of an adapter device by which my appliance may be installed upon curved doors.

There is illustrated formally, a fire-box 65 10', which may be built in any approved fashion, as followed in ordinary furnaces. In the front wall of the fire-box there is mounted the ordinary door and frame 10 and 11, in the present instance a rotary draft 70 shutter 12 being illustrated thereon to regulate the admission of air through openings 13 in the body of the door. Upon the inner surface of the door, there is bolted or otherwise secured my super-heater and burner 14, 75 which is in a box-like form, and projects a considerable distance into the fire-box from the door when the latter is closed, the burner being trapezoidal in plan with its convergent portions directed inwardly whereby it 80 may readily clear the door frame in the opening and closing movement of the door.

The device comprises a housing part including a main casting 15, which includes the bottom 16 and side walls 17, which are convergent toward their inner parts. At the front and also at the inner edges of these walls, they are joined at the top by cross bars 18 which are formed as continuations of retaining flanges 19 formed on the 90 side walls 17, immediately inward of which there are similar flanges 20 forming channels at the front and rear sides of the housing, in which there may be slidably received foraminated plates 21 and 22 respectively. 95 Intermediately of the housing additional flanges 20' are provided at each side in which a similar foraminated plate 23 is mounted, the perforations in which, however, are in 100 staggered relation to perforations in the first plates. It is also to be noted that there are no openings in the intermediate plate 23 immediately adjacent the upper and lower edges of the plate. The top of the housing is closed after insertion of the plates 21, 22 and 23 by means of a top plate 24, fitting 105 snugly between the bars 18 and suitably projected upper edges 25 of the side walls 17. Upon the rear or inner sides of the plates 21 and 23, there are secured vertically ex- 110

tended channel pieces 26, each having an open side, which is presented against the respective plate upon which it is mounted. Each channel member abuts against the bottom 5 of tom 16 and top plate 24 of the housing, and at the extremities has openings or ports 27 formed therethrough opposite the plates to which they are secured. The edges of the mutually adjacent channel members are spaced from each other as much as found desirable leaving some openings in the plates 10 21—23 uncovered, as may be seen in Fig. 4. They are secured upon the respective plates by means of bolts 28, engaged through suitable apertures in the plates and channel members, and held by nuts 29.

For attachment of the device to a door, central mounting ears 30 are removably secured to the top and bottom of the housing, as by screw bolts and nuts as shown 20 in Fig. 5. The ears 30 are apertured to receive ordinary stove bolts and may be engaged with the door in a familiar way.

In the event that it is desired to mount 25 the device upon a door having an inner flat surface, the housing may be presented directly thereagainst in the form described, and secured as indicated. In the event, however, that the door has a curved surface, 30 upon the inner side, an adapter device 31 is first secured to the front of the housing, one form of the adapter being shown in Fig. 6. It has an inner flat side adapted to fit snugly against the front side of the housing, being in a shape similar of outline to 35 that of the front of the housing. It is provided with ears 32 at the ends which may be secured by the screws 33 holding the top plate 24 in place at each end. The front side 40 is of a shape to fit snugly to the door, and provided with ears 30' suitably located to enable its mounting upon the door as desired.

It will be readily understood from the 45 foregoing that a simple appliance is provided, adapted to be manufactured at low cost, which is free from complications, requiring no special adjustment, and is liable in a minimum degree to damage. It is also 50 a very simple matter to put the device in place.

In the operation of the device, when properly secured upon a door and the door is closed, all of the exterior walls thereof will

be heated by the hot gases and fire-shine of 55 the fire-box. Air passing through the forward plate will be largely directed upwardly and downwardly by the channel members 26, and against the heated top and bottom walls of the housing. The movement of 60 such air from the ports 27 will then be largely away from the top and bottom, in order to pass through the intermediate openings of the plate 23, the channel members of which will again deflect the air upwardly 65 and downwardly against the hot top and bottom of the housing before it passes through the final very hot plate 22. The movement of the air caused by the channel members will also frictionally act upon that 70 air which passes directly through the plates 21 and 23 without the channel members, so that a thorough mixture of the highly heated air coming in contact with the walls of 75 the housing with that air passing through the intermediate parts of the plates will be attained. Passage through the plate 22 will finally heat the air to such an extent that when coming into contact with the already 80 heated carbon monoxide in the furnace the gases are nascent or in a ready condition for combination. The plates 21 and 23 and the channel members will also serve to heat air passing therethrough because of conduction 85 of heat from the housing to the plates. 85

What is claimed:—

A device of the character described comprising a cast housing having an opening extended therethrough from front to rear, and having transverse guide elements at intervals thereon, being constructed for, and having vertical planiform foraminate plates slidably inserted in said guides through one side of the housing so as to extend across the opening through said housing, certain 90 of said plates having channelled members mounted at one side and open adjacent the plates, and having openings in the sides opposite the plates upon which they are mounted, disposed to cause air admitted through 95 the plates to pass in a tortuous manner from one to another.

In testimony whereof I have affixed my signature in presence of two witnesses.

ALFRED F. TARDIE.
